CLAIM

The ornamental design for a container for perfume or the like, as shown and described.

DESCRIPTION

FIG. 1 is a front elevational view of a container for perfume or the like showing my new design;

FIG. 2 is a top plan view of FIG. 1;

FIG. 3 is a side elevational view looking from right to left at FIG. 1;

FIG. 4 is a side elevational view opposite that of FIG. 3;

FIG. 5 is a rear elevational view of FIG. 1; and FIG. 6 is a bottom plan view of FIG. 1.
